CALCULATING OR COMPUTING DEVICE

Felix Bardach, New York, N. Y.

Application December 15, 1948, Serial No. 65,361

4 Claims. (Cl. 235—61)

1

The present invention relates to computing or calculating devices and more specifically to a device for determining various data, such as sales volume, cost and profit of a business, of a product or line of products, or of operating a machine, plant, etc.

It is an object of the invention to provide means contributing to a very simple, but accurate and effective instrument, which facilitates evaluation of the effect of changes in business volume and of the results of price or cost changes with respect to profits.

It is another object of the invention to provide means ensuring determination of various essential characteristics on which business, production and like transactions depend whereby the breakeven or profitless point, the margin of safety or the percentage of sales above the breakeven point, as well as the profit factor or similar comparative relations may be visualized.

It is a further object of the invention to provide means enabling the engineer, the businessman, etc., to solve mathematical or graphical calculations in regard to efficiency in a quick and easy way and without resorting to complicated and cumbersome instruments heretofore proposed.

Yet another object of the invention is to provide means facilitating the practical construction of an inexpensive device or instrument of the aforesaid nature, which is only composed of a few parts which can be conveniently collapsed and transformed into compact condition when not in use.

Still a further object of the invention is to provide means affording movability of a plurality of swingable arms in lengthwise direction of an elongated base, whereby said arms may be displaced in a direction toward or from each other and swung in predetermined angular relation with respect to each other.

Another object of the invention is to provide means facilitating guiding of said arms and limiting the movements thereof with respect to predetermined positions on said base.

It is still another object of this invention to provide means offering the possibility of setting said arms to zero position with respect to said base whereby said arms and their supports are suitably shaped to take up a minimum of space.

With the above and other objects in view, the invention will be hereinafter more particularly described and the combination and arrangement of parts will be shown in the accompanying draw-

2

ings and pointed out in the claims which form part of the specification.

In the drawing,

Fig. 1 is a top plan view of the instrument or ruler device made in accordance with this invention with the arms thereof set in predetermined positions.

Figs. 2 and 3 are diagrams to which reference is made in the specification.

Fig. 4 shows the instrument of Fig. 1 in collapsed condition.

Fig. 5 is an end view of the instrument of Fig. 1.

Figs. 6, 7 and 8 are respective sectional views taken along lines 6—6, 7—7 and 8—8 of Fig. 1.

Referring now more particularly to the attached drawings, there is shown in Fig. 1 a ruler device or instrument 10 which comprises a body or base 11 with a recess or slot defining a runway 12 which slidably receives one or more slides, such as indicated by numerals 14 and 15, and coextensive side strips 16, 17 to retain said slide or slides in said recessed base. In the present instance, one of said side strips is provided on its top surface with scales 13, 19 to which reference is made further below. Carried and movably affixed to slide 14 is a first swing arm 20, whereas a second swing arm 21 is attached to slide 15.

Further secured to base 11 and within runway 12 are terminal stops 22a, 23a for engagement with slides 14 and 15, respectively, so as to limit the longitudinal movements of the latter. On the side strips 16, 17 of ruler 10 are arranged two pins 24, 25, which may be either fixed or retractable in axial direction of said pins and normally extend at the same level with respect to each other but project beyond the surfaces of said side strips.

As can be visualized from Figs. 1, 4 and 5 swing arm 21 is disposed on slide 15 at a higher level than swing arm 20, which is carried by slide 14.

Each slide 14, 15 is provided with at least one binding screw. In the embodiment shown a pair of binding screws 14a, 20a on slide 14 and a pair of binding screws 15a, 21a on slide 15 are employed of which screws 14a, 15a fulfill the function of displaceably securing the slides 14, 15 in any desired position lengthwise of slot 12 and of which screws 20a, 21a serve the purpose of adjusting the movable arms 20, 21 in any desired angular relationship to their respective slides, as well as with respect to each other.

Side strips 16, 17 are disposed alongside each other in spaced relation forming a slot defining a runway 22 therebetween, through which extend the screw bolts 15b (Fig. 8), 21b (Fig. 7) and 20b (Fig. 6). These screw bolts, respective-

ly, engage binding screws $15a$, $21a$ and $20a$ on slides 15 and 14 . It is well understood that a similar screw bolt connects slide 14 with binding screw $14a$.

Each screw bolt is provided with a suitably shaped head 23 to undisplaceably secure the respective bolt in place within the respective slide. In order to lock the respective binding screws suitable washers 26 are employed against which said binding screws may be tightened, as may be realized from Figs. 6 to 8.

Within the runway 22 between, but somewhat below side strips 16 , 17 and carried by or integral with slides 14 , 15 are arranged closure or filler plates $24a$, $25a$, respectively, which are preferably coextensive with said slides 14 , 15 and carry the markings 33 , 34 later referred to.

As will be apparent from Fig. 6 there is disposed on filler plate $24a$ a spacer or shim 27 of oblong shape which raises swing arm 20 above the upper surface of side strips 16 , 17 for the purpose of affording swinging movement of arm 20 relative to base 11 and to slide 15 . The latter may be secured in place on base 11 by means of binding screw $15a$.

Swing arm 21 is provided with a beveled portion 28 whose forward reading edge $28a$ comes to lie for contact on the top surface of swing arm 20 in operative position thereof.

Arm 21 has a hub portion 29 from which extends an offset part 30 which provides sufficient clearance above side strips 16 , 17 (Fig. 7) to allow arm 21 to assume a position above the level of top surface 31 of arm 20 .

Arm 20 is provided with one or more graduation of equal increment forming one or several scales 32 . It is to be observed that scales 18 , 19 and 32 are similar to each other for a purpose later described.

Slides 14 , 15 are provided with respective markings 33 , 34 for indicating the positions of said slides with respect to scales 18 , 19 . Arm 20 is further provided with a cut-out 35 which facilitates setting that arm 20 when moved by means of slide 14 to "zero" position (in which edge 36 abuts against stop pin 24 and edge 37 abuts against stop pin 25) which is indicated by dotted lines 40 , clears end 38 of slide 15 upon movement of the latter to its respective "zero" position, indicated by dotted lines 41 .

It results from the above construction of ruler or calculating device 10 that the same may be collapsed, when not in use as depicted in Fig. 4.

According to Fig. 4 slide 14 is displaced (upon loosening of binding screw $14a$) to outermost position adjacent stop pin $22a$, whereas slide 15 assumes a position in proximity of stop pin $23a$. Swing arms 20 and 21 (upon loosening of their respective binding screws $20a$, $21a$) are then moved to superposed position in which arm 20 is prevented from outward movement by means of stop pin 24 . Binding screw $21a$ may then be tightened to hold swing arm 21 in substantially aligned position with arm 20 and the body 11 of ruler instrument 10 .

In order to more clearly understand the operation of instrument 10 , it is to be observed that leg $10a$ forms the Y-axis (+) and leg $10b$ forms the Y-axis (-), both said legs being aligned with each other; arm or leg 20 forms the X-axis, whereas arm 21 constitutes the profit axis, which indicates above the "zero" line 40 any profit and below said "zero" line 40 any loss.

The Y-axis and X-axis form together the ordinates of a rectangular co-ordinate system.

It is apparent from Fig. 1 that Y-axis $10a$ — $10b$ 75

has one or more scales 18 , 19 of equal increment and that likewise the X-axis 20 is provided with one or more scales 37 of equal increment. These scales include each preferably a percentage scale (reading from 0 to 100). This percentage scale on the Y-axis (-) $10b$ is carried out only to the extent from 0 to 50 for practical purposes.

Let it be assumed that the instrument is to be used in connection with a business, in which, for example, for a specified period of time a turnover or sales volume is realized with definite fixed cost and variable cost yielding a certain net profit. This net profit is the result of sales less fixed and variable cost.

In order to determine the breakeven or profitless point of a business with the following hypothetical data:

Sales	\$3,000.00	Fixed Cost	\$ 450.00
		Variable Cost	\$1,350.00
Profit	\$1,200.00	Total Cost	\$1,800.00

one proceeds in the following manner.

The instrument 10 is set in operative position (from that shown in Fig. 4) by swinging arm 20 to assume a position indicated by numeral 40 of Fig. 1 in which edges 32 and 36 abut against terminal pins 24 , 25 . Binding screw $20a$ is then tightened against slide 14 to maintain arm or leg 20 in right angle position to leg $10a$ (Fig. 6). Subsequently arm 20 is moved by means of slide 14 lengthwise of slot 22 from "zero" position (in which marking 33 coincides with 0 of the scale 18) to a point of the scale corresponding to the profit of \$1,200.00 yielded in the analysed period (in which marking 33 coincides with 1200 of the scale 18 ; see Fig. 1). In this position slide 14 is maintained by manipulating binding screw $14a$ to be tightened against base 11 .

Thereafter, arm 21 is moved by means of slide 15 lengthwise of runway 22 from "zero" position (indicated at 41) to a point of the scale corresponding to the fixed cost of \$450.00 (in which marking 34 coincides with 450 of scale 19 ; see Fig. 1).

Slide 15 is then fixed in this latter position by tightening binding screw $15a$ against base 11 (Fig. 8).

Arm 21 is then swung to assume a position with respect to arm or leg 20 whereby edge $28a$ intersects edge 37 at a scale point 3000 corresponding to the sales volume or turnover of \$3,000.00 as contemplated.

Arm 21 in this intersecting angular position (as visualized in Fig. 1) is secured and held by means of binding screw $21a$ tightened against slide 15 in a manner similar to that shown and described with respect to binding screw $20a$ and slide 14 (Fig. 6).

While arm 21 extends in this fixed angular direction (Fig. 1) arm 20 (upon loosening of binding screw $14a$) is moved by means of slide 14 again to "zero" position (indicated by numeral 40) in which edge $28a$ of arm 21 intersects edge 37 of arm 20 at the scale point 818 (indicated by numeral 42 of Fig. 1 and diagrammatically illustrated in Fig. 2). This intersection between edge $28a$ and edge 37 determines the breakeven or profitless point.

It is important to note that the ratio of this breakeven point to the sales volume determines the soundness of the business; in other words, according to the example chosen

which indicates a margin of safety of 72.7% above the breakeven point.

In order to arrive at the percentage of profit for sales above the breakeven point, herein referred to as profit factor, arm 20 is moved with slide 14 lengthwise of slot 22 to a position where edge 28a of the still fixed angularly extending arm 21 intersects edge 37 at point 100 of the percentage scale of said arm 20. In this position of edge 37 of arm 20 marking 33 of slide 14 coincides with point 46 of the percentage scale 18 of leg 10a. This is made clear in the diagram of Fig. 3.

If one adds to value 46 thus obtained the value 9 (forming a point of the percentage scale 19 of leg 10b to which marking 34 points) then profit factor 55 is obtained as the sum of both readings on the Y-axis (+) and (-). This total value of 55 indicates that for each unit (dollar) sold above the breakeven point a profit of 55% (cents) is achieved.

It is well understood that the device may also be used to demonstrate any loss and relationship thereof to the breakeven point. In such case, it is desirable to employ retractable stop pins 24, 25 so that arm 20 may be moved along the negative leg 10b of the Y-axis.

It is further understood that any suitable material, such as wood, metal, plastic or plastic composition, may be used for the slotted base 11, its slides and for the levers or arms 20, 21 movable by means of said slides in the runway 22 of the base body 11-16-17.

It can thus be seen that there has been provided in the present invention a calculating device comprising an elongated base forming the Y-axis of a coordinate system, two spaced apart scales on the top surface of said base, two slide means arranged for sliding movement on said base in lengthwise direction thereof and movable independently of each other for cooperation with said scales, respectively, lever means swingably connected to said slide means, respectively, respective means securing in place said lever means on said slide means, and means for fixing said slide means relative to said base, at least one of said lever means forming the X-axis of said co-ordinate system and being provided with a scale, another of said lever means being positioned at a level above said one lever means to thereby intersect said scale of said one lever means.

While there has been shown and described a preferred embodiment of the invention, it is obvious that further changes may be made in the same without departing from the spirit of the invention.

Having thus described the invention, what is claimed as new and desired to be secured by Letters Patent, is:

1. A calculating device comprising an elongated support with a runway, a first slide in said runway, a first arm swingably mounted on said first slide, first binding means on said first slide for fixing same in selected positions along said runway and for fixing said arm thereon in selected angular positions relative to said support, a second slide in said runway, a second arm swingably mounted on said second slide, second binding means on said second slide for fixing same in selected positions along said runway and for fixing said second arm thereon in selected angular positions relative to said support, spacing means on said second slide maintaining said second arm sufficiently raised above said support to clear said first arm, and stop means beside said runway projecting from an intermediate portion of said support, said stop means being of a height sufficient to arrest said first arm but insufficient to interfere with the movement of said second arm, thereby enabling said second slide to move past said intermediate portion in any angular position of said second arm.

2. A calculating device according to claim 1, wherein said stop means comprises a pair of pins so positioned on opposite sides of said runway as to define a position for said first arm perpendicular to said support.

3. A calculating device according to claim 1, wherein said second slide carries a pivot element and said second arm is swingable about said pivot element and is provided with a reading edge aligned with the axis of said pivot element, said first arm being provided with a pivot and with an edge offset from said pivot having a main portion forming a reading edge and further having a recessed portion adjacent said first slide and adapted to accommodate said pivot element, said offset edge being engageable by said stop means.

4. A calculating device according to claim 3, wherein said stop means comprises a pair of pins so positioned on opposite sides of said runway as to define a position for said first arm perpendicular to said runway, said pins being staggered along said runway and being engageable by said recessed edge portion and by said main edge portion of said first arm, respectively.

FELIX BARDACHE.
